2,583,515

FLUID TREATING HELICALLY ADVANCING
THREADS

Thomas S. Mayner, Chagrin Harbor, Willoughby Township, Lake County, Ohio, assignor to Industrial Rayon Corporation, Cleveland, Ohio, a corporation of Delaware

Application November 20, 1947, Serial No. 787,147

2 Claims. (Cl. 8—151.1)

1

This invention relates to processing thread in a plurality of processing stages. More particularly, the invention relates to a method in which the plurality of stages are individualized so that the mingling of processing fluids is substantially entirely eliminated.

Reels operating on the principle disclosed in the Knebusch Patent No. 2,210,914 are of particular advantage in the continuous process for the manufacture of rayon yarn, thread, etc. Such two-member reels however have been utilized for the performance of single processing steps. The length of a two-member reel is somewhat limited due to the fact that the reel comprises two reel members one of which is offset and askew to the other. This arrangement prevents the construction of a lengthy reel whereon a plurality of processing steps can be performed since the bar members of one of the reel members when produced would interfere with the bar members of the other reel member.

A reel adapted for the performance of a plurality of stages and having a length limited only by the number of stages desired advantageously can be constructed by abbreviating the lengths of the eccentric reel members to enable the use of a plurality of such members, and a continuous concentric member. Such a reel will advantageously advance the thread or the like in the form of a uniform helix from stage to stage over its entire periphery. On a reel of this type, however, there can occur a mingling of processing fluids, for fluid from a previous stage may be carried by the thread to the next stage thus preventing a clean fluid processing on the succeeding step. It would be advantageous, of course, to substantially rid the thread of a processing fluid prior to a subsequent fluid treatment.

Advantageously during processing the thread turns are spaced closely together so as to enable the processing fluid to blanket the combined thread surface. If then, the fluid blanket is not destroyed at the end of a processing stage a substantial amount of fluid is carried over to the next processing stage. Since it is advantageous to fully blanket the thread turns on a single stage of a multiple stage reel the blanket should be destroyed and the fluid gotten rid of before the thread reaches the next stage. If the surface tension of the fluid blanket can be broken, for instance, by separating the thread turns, the processing fluid will be thrown off. It will also tend to drop into the reel between the thread bearing members collecting therein to be thrown out as a larger mass by the centrifugal force of the rotat-

2

ing reel. Also, depending upon the distance over which the turns are separated the thread can have performed on it other desirable treatments.

This invention advantageously provides for a thread turn spreading means forming a part of the reel which is adapted to separate the turns of thread after a processing step has been applied to thus destroy the fluid blanket covering the thread. The thread is then forwarded with a minimum of processing fluids to the succeeding stage for a further liquid application. Such a means comprises an intermediate abbreviated reel section rotating about an axis that causes a separation of thread turns a sufficient distance to break the surface tension of a fluid blanket covering the thread. This thread transfer section is further advantageously constructed so as to cause a minimum of thread distortion at the points of transfer from the one reel stage to the next.

The degree of thread turn separation is dependent, of course, upon the type of fluid treatment that is being applied to the thread since the thread need be separated only to such an extent so as to break the surface tension of the fluid blanket and not to impede the discarding of the fluid from within the reel members. The thread separating and transfer reel section is generally considerably shorter in length than the processing stages of the reel inasmuch as its function is primarily to spread a few of the thread turns in order to rid the thread of its fluid and to transfer the thread from one stage to another.

A thread turn separating section can also be advantageously utilized at the receiving or hub portion of a reel, or at the discharge end of a reel. Further, a thread turn spreading section in a reel can be of particular use on a reel adapted for the drying of yarn or thread.

The reel of this invention is advantageous, further, in that a plurality of separate or individualized processing steps can be performed on the thread while it moves over the reel periphery. The reel may comprise as many as five or six stages on each of which a fluid treatment can be performed and each such stage individualized by means of a transfer section.

The aforementioned reel is more thoroughly described in the attached specification and the accompanying drawing where:

Figure 1 is an elevation of a multi-stage reel; Figure 2 is a cross section of the reel; Figure 3 is an end view of the reel of Figure 1; and, Figure 4 is an isometric representation of the reel depicting individualization of the several stages.

Referring to the drawing the reel comprises a combination of several reel members forming a generally cylindrical device whose periphery is made up of a plurality of longitudinally extending bar members that cooperate to advance thread in a plurality of generally helical turns. One reel member 10 concentrically mounted about its axis, has bars 11 of continual length. The bars 11 are supported at one end by an equal number of radially extending supporting members 13 which merge into a hub 14 that is mounted on a reel supporting shaft 15. The hub 14 is held fixed to the shaft 15 by means of a set screw 17. The longitudinally extending bar members 11 at the other end merge into a flange 18 advantageously forming a ring that is fastened to a hub member 19 by means of screws 20. The hub member 19, in turn, is concentrically mounted about the shaft 15 on a concentric supporting sleeve 21 having a flanged end 22 through which the shaft extends. The flanged portion 22 of the supporting sleeve 21 is adapted to be received by a means provided for it (not shown) in the face of a spinning machine to thus support the reel from one end only. The thread is generally received at the hub portion of the reel and is advanced in a plurality of helical turns over the reel toward the unobstructed end.

Between the bar members 11 of the concentric reel member 10 there are positioned a plurality of bar members 27, 28, 29 forming peripheries of eccentrically positioned reel members 23, 24, 25. These reel members rotate about the shaft 15 on axes that are offset and askew to the axis of the concentric reel member 10. Further they are positioned in an end-to-end relation, and the ends of their bar members 27, 28, and 29, respectively, are desirably tapered at their transfer portions so that they extend in a contiguous relation for a portion of their lengths. For instance, bar members 27 are tapered at one end only that is, at their discharge end, while the intermediate bar members 28 of the transfer and thread turn spreading reel member 24 are tapered at both the receiving and discharge ends; and bar members 29 are also tapered at one end only. Further, to facilitate the transfer of the thread from one eccentric reel member to the next the surfaces of the contiguous portions of the bar members are also tapered; the thread will not, then, be subject to sharp edges. As shown in Figure 2, the axes of the eccentric reel members 23, 24, and 25 are not only offset and askew to the axis of the reel member 10 but they also are positioned so that they intersect. Such an arrangement of the axes advantageously permits the advancement of the thread without any noticeable distortion of the thread helix. Also, such an arrangement permits the construction of a reel having more than the two and three stage examples of the drawing.

The bar members 27 of the eccentric reel member 23 are radially supported by a hub 30 which is adapted to rotate on a sleeve bearing 31 that is positioned about an eccentric 32. The eccentric, in turn, is mounted on a longitudinally extending sleeve 33 in which the reel shaft 15 rotates. In like manner the bar members 28, 29 are supported by hubs 35, 36 rotating about eccentrics 37, 38 fixed on the sleeve 33. The hub members 35, 36 are also desirably mounted on anti-friction sleeve bearings 41, 42.

The eccentrics 32, 37, 38 are desirably fixed against rotation and against lateral displacement by means of serrations in their ends. The ec-

centrics and spacers 47, 48 are compressed against the end of sleeve 21 by an abutting collar 43 through which a set screw 44 is threaded into the shaft 15. The collar 43 rotates with the shaft and bears against an anti-friction washer 45. The spacers 47, 48 are likewise mounted about the sleeve 33 for properly locating the eccentrics. Of course, instead of the spacer the eccentrics themselves could be extended to abut each other. The eccentric reel members are maintained on the eccentrics by spring-type retainers 39.

As shown in the drawing the thread spreading transfer reel 24 is considerably shorter in length than reel members 23 and 25 for its function is to spread the thread turns so as to destroy the fluid blanket covering them and then to cast off the clinging excess fluid. Advantageously the aforesaid can be done over a relatively short distance and the reel need only be long enough to perform its function. The processing stages are individualized in a definite manner. Figure 4 shows how the fluid blanket is advantageously restricted to a definite area. The instant the turns are spread the fluid blanket is destroyed and the fluid is thrown off.

The shaft 15 extends somewhat beyond the supporting sleeve section 21 in order that a driving gear 50 may be mounted on such extension. Desirably positioned within the driving gear there is a slip clutch that is adapted to prevent an overloading of the reel. The slip clutch may comprise a sleeve 51 that is fixed to the shaft 15 by a set screw 52. The sleeve 51 has in one end radially extending spring-backed ball bearings 53. The ball bearings 53 are adapted to rest in recesses 54 provided for them in the inner annular surface of the gear 50. Thus, when an overload occurs the bearings are compressed permitting a rotation of the gear while the reel is either stationary or while it rotates at a lesser speed.

The aforesaid reel construction as isometrically shown in Figure 4 individualizes processing steps because of the construction and eccentricity of the intermediate reel transfer member 24. The member tends to spread the thread turns so as to destroy the fluid blankets 62 that cover them. The various fluids are applied by means of tubes 60 onto three eccentric members 23, 25 and 61 whereon the thread is closely spaced to form liquid blankets 62. The thread spreading transfer member 24, as stated, then spreads the thread turns to destroy the fluid blankets. The processing fluids tend to drop within the reel member 24 where they collect to form larger masses. The fluid is then substantially immediately thrown out and the thread enters the next stage substantially entirely free of the previous processing fluid. The thread is thus prepared for a succeeding processing step which is applied on the following reel section determined by the next eccentric reel member.

While in the drawing Figures 1 and 2 show the use of only two processing stages the reel can be extended as long as desired and as illustrated in Figure 3 providing the arrangement of the reel sections is such so as to prevent any interference between the adjacent bar members. A thread separating section would be, of course, positioned between each eccentric reel member upon which the processing step is performed.

I claim:

1. The method for processing thread or the like with a fluid a plurality of times as the thread is continuously advanced in a plurality of generally

helical turns consisting, closely spacing the thread turns, applying a processing liquid to said closely spaced turns to form a liquid blanket thereon, individualizing a predetermined plurality of said closely spaced turns by separating said turns to destroy the processing liquid blanket, collecting said liquid to form a mass sufficient to be thrown out of said helix by centrifugal force, then again closely spacing the thread turns for a subsequent application of a blanket of processing liquid.

2. The method for processing thread or the like, consisting of; forming a helix of liquid wetted thread having a plurality of consecutive turns; advancing said helix in a plurality of widely spaced thread turns, the turns being spaced to destroy and to prevent the formation of a coating blanket of the liquid that is carried by the advancing thread helix and to remove the liquid; then advancing said helix in a plurality of closely spaced thread turns spaced so as to support a thin liquid coating blanket; forming a thin coating of fluid treating liquid on the closely

spaced thread turns by applying a fluid treating liquid thereto; then removing the applied treating liquid by advancing the said helix in a plurality of widely spaced thread turns.
